VENDING MACHINE

Harry B. Stoner, Aurora, Ill.

Application June 19, 1946, Serial No. 677,735

14 Claims. (Cl. 194—57)

1

The invention relates generally to improvements in vending machines and more particularly to improvements in coin-control mechanisms of a kind adapted to be associated with such a machine and of a character to be operated manually by the customer upon insertion of one or more coins.

The structure constituting the subject matter of the present invention is primarily intended to be incorporated in a vending machine of the character shown and described in Stoner et al., United States Patent No. 2,824,040, dated July 13, 1943. It should be understood, however, that the invention may be incorporated in a vending machine embodying structural details other than as shown in said patent.

In the vending machine disclosed in that patent and shown in the accompanying drawings herein, several commodities are arranged in stacks or columns and are adapted to be discharged one at a time upon manual operation of selective discharge means. The discharge means normally is locked against actuation by a coin-control mechanism of a kind that is rendered operable upon insertion into the machine of one or more coins of like denomination; thus, the vending machine is made suitable for vending merchandise of different values which is discharged upon insertion into the machine of the required number of coins.

It is, therefore, an object of the present invention to provide a vending machine of the character referred to with novel and improved coin-control mechanism operable, when the required number of coins have been inserted, in response to manipulation of means operative to actuate mechanisms for discharging a piece of merchandise of a predetermined value.

Another object is to provide an improved coin-control mechanism for locking the discharge mechanism of a vending machine.

Another object of the invention is to provide a coin-control mechanism of a kind that may be fabricated from parts manufactured entirely by stamping operations.

Another object of the invention is to provide a novel structure whereby one or more coins of like denominations deposited in the machine may be returned to a customer should he decide not to obtain the merchandise initially selected.

Another object of the invention is to provide novel means actuatable upon manipulation of coin return means to release and discharge any bent or fraudulent coin which, if deposited in the machine, is incapable of following the usual coin passageway.

2

Other and further objects of the present invention will be apparent from the following description and claims and are illustrated in the accompanying drawings which, by way of illustration, show a preferred embodiment and the principle thereof and which is considered to be the best mode contemplated for applying that principle. Other embodiments of the invention embodying the same or equivalent principle may be used and structural changes may be made as desired by those skilled in the art without departing from the present invention and a purview of the appended claims.

In the drawings:

15 Fig. 1 is a perspective view of a vending machine embodying the features of the present invention.

Fig. 2 is an enlarged fragmentary side elevational view of the coin-control mechanism showing 20 the vending machine housing in section.

Fig. 3 is a vertical sectional detail view of the coin-control mechanism, taken substantially on line 3—3 of Fig. 2.

Fig. 4 is an elevational view looking at the 25 side face of the coin-control mechanism, taken substantially along the line 4—4 of Fig. 3.

Fig. 5 is a horizontal sectional view taken on line 5—5 of Fig. 4.

Fig. 6 is a vertical sectional detail view through 30 the coin-control mechanism, taken substantially on line 6—6 of Fig. 3, and showing the sliding members in elevation.

Fig. 7 is a detail view similar to Fig. 6 but showing 35 a part of the coin-control mechanism in elevation and two of the sliding members in coin-discharge position.

Fig. 8 is a horizontal sectional view taken substantially on line 8—8 of Fig. 2 and illustrating one of the stacks and the related merchandise vending operating mechanism in plan.

Fig. 9 is a sectional detail view showing a fragment 40 of the mechanism shown in Fig. 8, and illustrating the coin-control mechanism in an intermediate position of operation.

Fig. 10 is a sectional detail view like Fig. 9, but showing the coin-control mechanism in another position assumed during an operating cycle.

Fig. 11 is a fragmentary elevational view of the vending actuating mechanism and the coin-control mechanism as viewed from the front of the machine, and taken substantially along line 50 11—11 of Fig. 8.

Referring to the drawings and particularly to Fig. 1 thereof, the coin-control mechanism of the 55 present invention is mounted within a vending

machine of a character substantially like that shown. The vending machine includes a base portion 11 and an upper portion 12, the latter having a window opening 13 in its front wall 14 through which merchandise or representations thereof may be viewed. The merchandise or the representations thereof viewed through the window opening 13 correspond to the actual merchandise to be vended and contained within the upper portion 12 of the vending machine. Said merchandise is arranged therein in stacks or columns such as is indicated at 16, which stacks are separated by vertically disposed partition walls 17, each having hingedly mounted thereon, in a manner so as to normally be held horizontally, a plurality of plates or shelves 18 each of which is adapted to support an article of merchandise in the stack. The shelves 18 are constructed and mounted so that the shelves in each stack may be successively dropped into substantially vertical positions so as to permit the merchandise supported thereon to drop downwardly during machine operation and to be delivered to the customer through a vending opening 19.

The specific means for releasing the shelves 18 successively so as to drop a piece of merchandise into the vending opening 19 includes a plurality of plungers 21, one associated with each stack, which extend through openings 22 in the front wall of the vending machine housing. The plungers are effective when pulled outwardly to actuate suitable operating mechanism, generally illustrated in Fig. 8, effective to permit the release of a latch mechanism 20, operatively connected to the plunger by a rod 28', holding the lowermost shelf 18 of the respective stack when initially operated, and each successive operation of the said plunger actuates other latches like latch 20 to release the next higher shelf. In this manner the pieces of merchandise contained in a single stack are successively vended, the lowermost piece being the first one discharged.

The specific latch mechanism and operating mechanism for effecting successive release of the shelves is fully shown and described in the Stoner patent aforesaid, and because it constitutes no part of the present invention, a limited disclosure and brief description of the operation of the operating mechanism is all that is thought to be required herein for an understanding of its operation and relationship to the coin-control mechanism of the present invention. Upon referring to Figs. 8 and 11, it will be observed that each plunger 21 carries a vertically disposed actuating rod 23 which extends upwardly therefrom and is guided in a transverse slot 24 in the upper flange 25 of a guide channel 26 arranged on the front side and adjacent the lower ends of the combined stacks 16. Inasmuch as the construction of the operating mechanism associated with each stack is substantially identical, with variations in the mechanical adjustment of certain parts thereof, the following description concerns itself with one such mechanism only.

A journal pin 27, provided closely adjacent to the plunger 21, is firmly secured at its ends in the upper and lower flanges of the channel 26, as shown, and it carries a set of crank arms 28, one located above the other and suitably spaced apart, each having a forwardly extending arm 29 suitably apertured to receive pintle pins 31 for pivotally connecting the ends of said arms one to each of a set of draw bars 32 which extend longitudinally across the front of the guide channel 26.

In the embodiment shown there are three crank arms in each set, with the corresponding arms in each set disposed in horizontal rows, and a draw bar 32 connected one with all of the crank arms in each horizontal row. The crank arms mounted on any one of the journal pins 27 are adapted to operate either singly or in combinations of two or more. Each crank arm 28 has an enlarged portion disposed on one side of the journal pin 27 which includes a shoulder 33 normally disposed closely adjacent to the vertical rod 23 on the related plunger 21. Links 34, one associated with each crank arm 28, are each pivotally mounted at one end on the related pintle pin 31, and each has its other end suitably shaped to provide a downwardly extending lug 35 which normally lies in the path of the associated vertical rod 23. Springs 36, suitably anchored at 37 on each crank arm 28, have one end engaged in an ear 38 formed along one edge of the related link 34 and extending upwardly through an arcuate slot 39 in the related crank arm 28.

Upon reference to Fig. 11 it will be noted that the three crank arms 28 and links 34 constituting each set of operating mechanisms are identified therein by the indices a, b and c. As there shown, the lugs 35 on all of the links 34 are disposed in the path of the vertical rod 23 so that when the plunger 21 is pulled outwardly to operate the vending machine, the crank arms 28 will be swung about their pintle pin 27 thus shifting the draw-bars 32 connected therewith longitudinally across the front of the machine. Each of the crank arms 28, constituting the set of crank arms associated with the stack at the extreme right hand end of the machine, as viewed in Fig. 1, has an arm extension 41 carrying a knob or roller 42 which coats with a coin control mechanism, generally indicated at 43, which is effective normally to prevent actuation of any set or sets of the actuating crank arms 28.

The coin-control mechanism, which embodies the features of the present invention, is designed to effect an unlocking of a selected operating mechanism upon the insertion of one or more coins of like denominations so as to render such operating mechanism actuatable to vend an article of merchandise of a value corresponding to the number of coins deposited. To accomplish this, each set of crank arms 28 and their associated links 34 may be adjusted so that one, two or all three crank arms in any set will be swung about their common pintle pin 27 when their associated plunger 21 is pulled outwardly. This adjustment is effected by adjusting the position of one or two of the links 34 of a set. For example, should the top link 34 of the set of bell cranks 28, shown in Fig. 11, be shifted by grasping its ear 38 and moving it toward the opposite end of the slot 39 so that its lug 35 is out of the path of the vertical rod 23, outward movement of the related plunger 21 will result in rotation of the two lowermost crank arms 28 of said set only, the upper crank arm remaining stationary. Similarly, should the top and the intermediate links 34 be rendered ineffective in the foregoing manner, only the lower crank arm 28 will be actuated when the plunger 21 is pulled outwardly. It will thus be apparent that the actuating mechanisms associated with each stack of merchandise may be adjusted to permit the vending of merchandise of different values. For example, the merchandise contained in the right hand stack, when the merchandise is viewed as in Fig. 1 and as shown in Figs. 8 and 11, will be a twenty cent item because all of

the crank arms in the set are operatively connected to the plunger 21. Other stacks may contain merchandise to be dispensed for five or ten cents and, accordingly, the actuating mechanism associated with said stacks will be suitably adjusted to cause rotational movement of one or two of the crank arms in the manner aforesaid.

The coin-control mechanism, generally designated by the numeral 43, includes a plate assembly comprising a main plate 44 and an auxiliary plate 45 which are joined together as by means of rivets 46 which extend through inwardly struck protuberances 47 in the auxiliary plate 45. The protuberances 47 are provided to maintain the plates 44 and 45 in spaced relationship, with the distance between them being slightly greater than the coin for which the mechanism is designed.

In the embodiment shown, the space between the plates is of a size to correspond to the thickness of a five cent piece. The main plate 44 is substantially rectangular in shape and is provided at its bottom with a base flange 48 having openings 49 to accommodate pins 51 which extend upwardly from a floor plate 52 in the vending machine. As best illustrated in Figs. 4 and 5, one of the pins 51 has a head 53 to engage over the margins of the opening 49 when the pin is inserted through said opening and the plate assembly moved forwardly. The other pin 51 is of a length greater than the length of the headed pin 51 so as to be received within an opening 54 in a latch 55 pivotally secured at 56 to the main plate 44 and normally held tightly wedged therein by means of a tension spring 57 associated with said latch 55. A finger projection 58 is formed on the upper edge of the latch 55 so that said latch may be manually rotated about its pivot 56 for disengaging the pin 51 from the opening 49 therein to facilitate removal of the coin-control mechanism from the vending machine for any purpose whatsoever.

The upper margin of the main plate 44 is offset outwardly to define a flange 59 to provide for the attachment of a coin-mechanism 61. This coin-mechanism 61 is of a standard construction, and as it forms no part of the present invention it is not thought necessary to describe the same in great detail. It should be noted, however, that said mechanism includes a magnet 62 for detecting fraudulent coins and a jam-release mechanism including a hingedly mounted plate 63 and a release trigger 64. Coins inserted into the machine through a coin slot 65 in the front wall thereof pass through a guide trough 66 and downwardly between a wall of the coin mechanism and the plate 63. The release trigger 64 is pivotally mounted at 67 and is suitably slotted at 68 to receive therethrough a guide pin 69, which slot and guide pin limit movement of the trigger 64 about its pivot 67. A stud 71, carried by said trigger, extends through a slot 72 in the back wall of the coin mechanism 61 and cooperates with the hingedly mounted plate 63 in such manner that when the release trigger 64 is depressed, in a manner to be explained in detail hereinafter, the hingedly mounted plate 63 is moved outwardly away from the opposed wall of the coin mechanism 61 so as to increase the space between said hingedly mounted plate 63 and said wall to thereby enable any coin of a thickness greater than that intended to be passed through the coin mechanism to be released and deposited in a coin return chute 73.

The coin return chute 73 is located on the out-

side face of the auxiliary plate 45 and it consists of an elongated sheet metal stamping formed substantially U-shaped and having its open face disposed towards the auxiliary wall 45. The coin chute may be secured to said wall in any suitable manner, but preferably is firmly attached thereto by having portions thereof extending through holes in the auxiliary wall 45 and bent over against the opposite face thereof. The lower end of the intermediate wall portion 74 of the coin chute is deflected inwardly at an incline, as at 75, and extended through substantially square aligned openings 76 in the main and auxiliary plates 44 and 45 so that coins passing downwardly therethrough are discharged inwardly of the coin-control mechanism and received in a suitable coin return receptacle 77 located on the outside of the vending machine, as shown in Fig. 1.

Two lugs 78 and 79 are struck inwardly from the main plate 44, as best shown in Figs. 4, 6 and 7, so as to provide a passageway between the plates 44 and 45 to receive good coins of the correct denominations that pass through the coin mechanism 61. The coins entering between the lugs 78 and 79 drop downwardly between the plates 44 and 45 and normally rest with the lowermost coin seated upon the top surface of a support 81 which extends through the openings 76 in the main and auxiliary plates 44 and 45 and bridges the space between said plates. The support 81 comprises the top wall of an inverted U-shaped coin-release element, generally indicated at 82, which is fashioned from sheet stock and has its downwardly extending side wall portions 83 pivoted by means of a pin 84 to a pair of spaced apart lugs 85 struck out of and extending inwardly from the main plate 44 closely adjacent to the base flange 48. A spring 86 normally retains the coin-release element in the position shown with its intermediate wall portion 81 extending through the openings 76. Means is provided, which will be described presently, for imparting a rocking motion to the coin-release element to a sufficient extent as will withdraw the wall support 81 from its normal position to permit any coins supported thereabove to be discharged onto the inclined portion 75 of the coin return chute.

The main plate 44 is provided with a plurality of horizontally disposed vertically spaced slots 87 through each of which extends a horizontal wall portion 88 of a sliding member 89, which has its main body portion 91 disposed between the main plate 44 and the auxiliary plate 45. The main body portion 91 of each of these sliding members is of a width substantially equal to the diameter of a coin of a denomination to be used for operating the vending machine, and said body portions rest substantially with their opposed edges closely adjacent one to the other, as best shown in Fig. 6. The sliding members 89 are intended, upon insertion of the proper number of coins and during subsequent machine operation, to slide longitudinally a distance corresponding to the length of the horizontal slots 87 through which the wall portions 88 extend.

Sliding movement of said sliding members is, however, normally prevented in the absence of any coins having been inserted into the coin-control mechanism by a stop lug 92 extending from one edge of the intermediate wall portion 93 of a substantially U-shaped locking mem-

ber 94, one of which is associated with each

sliding member 89. The locking members 94 are fashioned from sheet stock and they have their side wall portions 95 pivotally mounted adjacent their free ends upon a vertically disposed shaft 96 journaled at its ends in spaced lugs 97 struck outwardly from the body of the main plate 44. Springs 98, one connected at one end to one of the wall portions 95 of each locking member and at its other end to an edge flange 99 on the coin-control mechanism, normally hold said locking elements in a position with their lugs 92 extending through related openings 100 in the main plate 44 and into the path of the related sliding members 89. It should be quite evident at this time that when a stop lug 92 is positioned in the path of a sliding member, said sliding member cannot be shifted out of the position substantially as shown in Fig. 6.

Sliding movement of one or more of the sliding members 89 is required to permit actuation of the vending operating mechanism described hereinbefore, inasmuch as each of the sliding members 89 is operatively connected with the actuating mechanism through interconnection of the rollers 42 on the crank arm extensions 41 with the wall portions 88 of said members. Upon referring to Fig. 8, it will be observed that each of the wall portions 88 of the sliding members 89 is suitably recessed at 101 to receive for slideable reciprocation therein the roller 42 of one of the crank arm extensions 41, thus each sliding member 89 is connected with one crank arm 28 of each set and is adapted to be moved simultaneously therewith.

When one coin of a predetermined denomination, which in the present instance is a five cent piece, is deposited into coin mechanism 61, it passes through the passageway between the lugs 78 and 79 and comes to rest upon the supporting wall 81 in alignment with the lowermost sliding member 89. When a plunger 21, related to a stack of commodities of a kind to be vended for five cents, is pulled outwardly, the bottom crank arm 28 in the related set of actuating means is engaged by the vertical rod 23 on said plunger and rotated, which rotation is transmitted through the related connecting bar 32 to the crank arm having the arm extension 41 engaged with the lowermost sliding member 89. Thus, the lowermost sliding member 89 is caused to move independently of the companion sliding members; such movement, however, being permitted only upon withdrawal of the stop lug 92 normally blocking its path.

Withdrawal of the stop lug 92 is obtained by means of a cam element 102 pivotally connected at one end, as by a screw 103, to the wall portion 88 of said sliding member and having its free other end extending through a slotted opening 104 in the intermediate wall portion 93 of the related locking member 94. The cam element 102 is formed by a stamping operation from sheet stock and is best shown in Fig. 8. It includes a projecting end portion 105 which extends through aligned slots 106 and 107 in the main plate 44 and auxiliary plate 45 so as to define with the lug 92 means to prevent initial displacement of the coin. The intermediate portion of the cam element 102 is offset outwardly, away from the main plate 44, as at 108, to present opposed pairs of cam surfaces 109 and 111 sufficiently spaced apart so as to allow the intermediate portion of said cam element to pass through the slotted opening 104 when the sliding member 89 is advanced. Initial advancement of the sliding mem-

ber 89 carries the cam element 102 into substantially the position shown in Fig. 9 at which time the cam surfaces 109 thereon are about to enter the slotted opening 104. In Fig. 10 the sliding member is shown in a position of further advancement, at which time the offset portion 108 has entered the slotted opening 104 and caused the locking member 94 to be rotated about its shaft 96 sufficiently to carry the lug 92 out of the path of the body portion 91 of the sliding member so that said member now is free to slide the entire distance required to effect actuation of the discharge mechanism and vending of the merchandise selected.

It should be observed at this time that the presence of a coin between the end portion 105 and lug 92 has prevented the free end of the cam element 102 from being cammed into the slots 106 and 107 during its advancement from the position illustrated in Fig. 9 toward the position illustrated in Fig. 10. Were this to occur, no movement would be imparted to the locking member 94 and the stop lug 92 would remain in the path of and block further sliding of the sliding member 89. Thus, the coin holds the free end of the cam element 102 in the position shown so that entrance of the cam surfaces 109 into the slotted opening 104 cams the locking member 94 outwardly to withdraw the lug 92 in the manner aforesaid.

As the sliding member 89 moves from the position shown in Fig. 8 into the extreme sliding position, the coin is pushed along in advance of said sliding member and is discharged, as best shown in Fig. 7, into a coin receiving passageway 112 which delivers the coin into a coin receptacle contained within the base of the vending machine.

In instances where a commodity to be sold for ten cents is desired, the customer will insert two coins of like denomination into the coin mechanism 61 and said two coins will assume positions substantially as shown in Fig. 6, with one in alignment with each of the two lowermost sliding members 89. When the corresponding plunger 21 is pulled outwardly, two of the crank arms 28 in the set of crank arms associated with said plunger are actuated to impart sliding movement to said two sliding members, at which time the cam elements 102 associated therewith are made effective to move the lugs 92 out of the paths of said two sliding members so that they may complete their stroke and discharge both coins into the discharge passageway 112.

Should it be desired to obtain a piece of merchandise vended for twenty cents, the customer will deposit four coins of like denomination into the coin mechanism 61, and these coins will be supported one in horizontal alignment with each of the two lowermost sliding members 89, and the two remaining coins in alignment with the dual end portion 113 on the uppermost sliding member 89a. Upon reference to Fig. 4, it will be observed that the sliding member 89a has a pair of cam members 102 connected thereto in the same manner as the cam members 102 are connected to each of the two lowermost sliding members 89. Each one of this pair of cam members 102, connected to the sliding member 89a, is associated with a locking member 94 so that manipulation of the correct plunger 21 will cause the three sliding members to be advanced so as to simultaneously carry all of the locking members 94 out of locking position.

It should be understood at this time that any combination of sliding members and locking members 94 may be embodied in the present mechanism so that, for example, commodities valued at ten, fifteen and twenty cents may be vended, in which instance a sliding member similar to that indicated at 89a would be positioned at the bottom of the series of sliding members to thereby prevent machine operation upon the insertion of a single coin.

The motion of any or all of the sliding members 89 must be completed to the ends of the strokes to prevent fraudulent manipulation of the device. This is accomplished by providing a pawl 114 on the coin-control mechanism, as shown in Fig. 2. The pawl 114 is mounted for free rotation on a pin 115 and is held normally with its engaging portion 116 substantially vertical by two tension springs 117 which are connected one to each of a pair of legs 118 substantially diametrically opposed to the engaging portion 116. Pins or studs 119 projecting outwardly from the auxiliary plate 45 provide means for securing the other ends of the springs in place. In the construction illustrated the auxiliary plate 45 has a horizontal slot 121 through which a block 122 extends. The block 122 is firmly secured to the back face of the lowermost sliding member 89 as by means of rivets 123, and its lower edge is serrated to provide teeth 124 disposed in a plane to cooperate with the engaging portion 116 on the pawl 114 when the sliding member 89 is moved during machine operation. In operation, as the said sliding member 86 is moved to the right, as viewed in Fig. 2, the serrated edge 124 will engage the engaging portion 116 and move the pawl in a clockwise direction, in which position the sliding member 86 can continue moving to the right; but if this movement is stopped while the engaging portion 116 is still in engagement with the teeth 124, the motion cannot be reversed to the left. However, when the stroke of the sliding member 86 has been completed to such an extent that the block 122 is moved past the pawl 114, the pawl will again resume its normal substantially vertical position. When the stroke is then reversed, the pawl 114 will again be effective to prevent anything but a completed return stroke for the sliding member 89.

Should a customer desire to have any coin or coins deposited in the coin slot returned to him without completing the operation of the machine and obtaining the commodity originally selected, he may actuate suitable means to permit said coins to be discharged therefrom. Such means is best shown in Figs. 2 and 3, and it includes a bell-crank lever 125 which is fashioned from sheet stock and is pivotally mounted at 126 on a bracket 127, also fashioned from sheet stock, firmly secured, as by welding, to the outside face of the end wall of the right hand stack located adjacent the coin-controlled mechanism. The bell-crank lever 125 has an arm portion 128 which extends upwardly from the pivot 126 and is provided on its free end with an angularly disposed finger engaging portion 129. This finger engaging portion 129 is located to the rear of an opening 131 in the front wall of the vending machine housing 12, or is otherwise so disposed as to be readily accessible for engagement by the customer. The bracket 127 has its upper margin bent out of the plane thereof substantially horizontally to provide a flange 132 having a slot 133 therein through which the arm portion 128

extends and which affords means for limiting movement of said arm about its pivot 126.

The other arm 134 of said bell-crank lever 125 extends rearwardly and downwardly from the pivot 126 and then horizontally to dispose its free end 135 through a slot in a vertical flange 136 bent from the rear end of the bracket 127, so as to be guided therein. This flange also carries a stud 137 engageable in a hole in the end 10 of the flange 99 on the rear edge of the coin-control mechanism to hold said mechanism in place. A spring 138 having one end connected to the arm 134 and its other end anchored in the horizontal bracket flange 132 normally retains the bell-crank lever in the position of rest illustrated in Fig. 2. It should be quite evident that when the finger engaging portion 129 is pushed inwardly of the housing by the customer, the bell-crank lever is rotated about its pivot 126 in a clockwise direction against the tension of spring 138.

A pin 141 extending outwardly from one face of the arm 134 of the bell-crank lever 125 is disposed immediately above the coin-release trigger 64 so that when the bell-crank lever 128 is rotated in a clockwise direction, as viewed in Fig. 2, the pin 141 will cause the coin-release trigger 64 to be moved about its pivot 67 to swing the hingedly mounted plate 63 of the coin mechanism away from the wall thereof so as to release any jammed coin or coins having a thickness greater than the thickness of the coin the mechanism is adapted to receive. Such coins as are released upon movement of the movable plate 35 63 fall into the coin return chute 73 and are returned to the customer.

Movement of the bell-crank lever 125 acts also to depress a bar 142, loosely connected thereto, as by means of a rivet 143, which extends vertically between the vending machine casing and the coin-control mechanism and has its lower end bent substantially at right angles thereto to define a foot portion 144 that overlies a lug 145 struck out of one of the side walls 83 of the coin support 82. A spring 146 retains the bar 142 in actuatable position with relation to the bell-crank lever 125, but when said bell-crank lever is rotated to actuate the coin-release trigger, the bar 142 is carried downwardly thereby so that its foot portion 144 engages the lug 145 to rock the coin support 82 about its pivot so as to withdraw the supporting wall portion 81 from beneath the coins supported thereby between the spaced apart plates 44 and 45. Such coins as are released upon withdrawal of the wall portion 81 of the coin support 82 drop onto the inclined surface 75 of the coin-return chute and are likewise returned to the customer.

It should be understood that the mechanism disclosed in the accompanying drawings and described in detail in the foregoing description lends itself to be manufactured entirely by stamping operations and that it may embody various modifications in detail structure without departing from the spirit of the invention and the scope of the appended claims.

I claim:

1. In a vending device of the character described including a plurality of stacks for supporting commodities therein and normally inoperative operating means associated with each of said stacks for causing said commodities to be delivered from said stacks one by one, a coin-control mechanism associated with said device for releasing said operating means including

sliding members and blocks normally blocking said sliding members, and coin positioned cam means carried by said sliding members movable during initial movement of said sliding members in the presence of coins into positions to engage and remove the blocks from the paths of the sliding members.

2. In a vending device of the character described including a plurality of stacks for supporting commodities and operating means including levers arranged in sets associated with each of said stacks for causing said commodities to be delivered from said stacks one by one, a coin-control mechanism associated with said device for releasing said operating means, said mechanism comprising a plurality of sliding members one operatively connected to one or more levers in each of said sets of levers, means normally locking said sliding members against movement to prevent actuation of said operating means, said locking means having a slot therein and cam means on said sliding members, said cam means extending through the slot in a related locking means and each having a portion thereof disposed for engagement by a coin so that one or more of said cam means is effective upon the insertion of one or more coins of like denominations to unlock the corresponding number of locking means and permit operation of the operating means connected thereto.

3. In a coin-control mechanism including spaced apart plates between which a coin is adapted to pass, a sliding member between said plates and extending through one of said plates, a cam element on said member extending through a slot in said one plate into the space between them, and a locking member to prevent sliding movement of said sliding member, said locking member and said cam element being operatively associated so as to move the locking member into unlocking position when a coin is located between the plates in the path of said cam element to prevent its extending into the space between the plates.

4. In a coin-control mechanism including spaced apart plates between which a coin is adapted to pass, a sliding member, a cam element on said member extending through a slot in one of said plates into the space between them, a locking member to prevent sliding movement of said sliding member, said locking member and said cam element being operatively associated so as to move the locking member into unlocking position when a coin is located between the plates in the path of said cam element to prevent its entrance into the space between the plates, and means on the cam element to prevent displacement of the coin.

5. A coin-control mechanism for a machine for vending commodities of various values comprising a plurality of sliding members, means normally blocking said sliding members, cam elements one carried on each member operatively associated with the blocking means, said cam elements each having a portion thereof engageable by a coin to as to be positionable to cam the related blocking member into unblocking position upon movement of the sliding members when coins are located one in a predetermined position relative to each sliding member.

6. A coin-control mechanism for a machine for vending commodities comprising a plurality of sliding members, means normally blocking said sliding members, cam elements one carried on each sliding member operatively associated

with the blocking means, one of said cam elements having a portion thereof engageable by a coin so as to be positionable in the presence of a coin to cam the related blocking member into unblocking position during initial movement of the related sliding member so as to permit said sliding member to move through its complete path of travel.

7. A coin-control mechanism comprising spaced plates, a plurality of sliding members arranged between said plates, separate means normally locking each of said members against sliding movement, and cam elements one connected at one end to each sliding member and having its other end slidably engaged with the related locking means effective to move the said locking means into an unlocking position when a coin is associated therewith so as to permit the sliding of the related sliding member.

8. A coin-control mechanism comprising a pair of plates spaced apart a distance slightly greater than the thickness of a coin of a predetermined denomination, means to direct a coin along a predetermined path between said plates, a plurality of sliding members arranged edge to edge between said plates, said members having abutting shoulders on their opposed edges to render said members selectively movable in succession, blocking members pivotally mounted on one face of one of said plates, each including a lug normally extending between the plates to prevent movement of the sliding members, and a cam element carried by each sliding member and slidably in a related locking member so as to unlock the related locking member when a coin is aligned with the related sliding member between the plates and said sliding member is moved.

9. A coin-control mechanism comprising a pair of spaced apart plates, means to direct a coin along a predetermined path between said plates, a plurality of sliding members arranged edge to edge between said plates, said members being of a width corresponding to the diameter of a coin of predetermined denomination and having abutting shoulders on their opposed edges to render said member selectively movable in succession, blocking members pivotally mounted on one face of one of said plates, each including a lug normally extending between the plates to prevent movement of the sliding members, cam elements one carried by each sliding member and one slidably connected with a related locking member, said cam elements being effective to unlock the relating locking members when a number of coins corresponding to the number of slide members is aligned with the related sliding member between the plates.

10. A coin-control mechanism comprising spaced apart plates adapted to receive a coin therebetween, one of said plates having a plurality of slots therein, a plurality of sliding members arranged between said plates, a wall portion on each sliding member extending one through each slot, cam elements pivotally connected at one end to each wall portion, the plate having additional slots underlying the free end portions of said cam elements, a plurality of locking members pivotally mounted on the slotted plate each having a stop lug normally rested in the path of one of the sliding members, means to support a coin between the plates in position to coat with the free end portion of one of the cam elements so that when the vending machine is actuated to vend an article for which a coin

has been deposited said cam element coacts with the locking member to move the locking lug out of the path of the sliding member.

11. A coin-control mechanism for a vending machine including normally locked selectively actuatable operating means, said mechanism comprising spaced apart plates adapted to receive a coin therebetween, one of said plates having a plurality of slots therein, a plurality of sliding members arranged between said plates, a wall portion on each sliding member one extending through each slot and operatively connected to one or more of said operating means, cam elements pivotally connected at one end one to each wall portion, the plate having additional slots underlying the free end portions of said cam elements, a plurality of locking members pivotally mounted on the slotted plate each having a stop lug normally rested in the path of one of the sliding members, means to support a coin between the plates in position to coact with the free end portion of one of the cam elements so that the effected cam element is positioned to move the locking lug out of the path of its associated sliding member whereby said member may slide in response to selective operation of the operating means connected thereto.

12. A coin-control mechanism for a machine having a plurality of stacks for supporting commodities therein and operating means associated with each stack for causing said commodities to be delivered selectively from said stacks one by one, said mechanism comprising slidable members adapted to be linked to each of said operating means, means normally locking said sliding members to prevent actuation of the operating means, and a cam element on each of said sliding members, said cam elements being slidably connected one with each locking means and each being adapted to have a coin associated therewith to render it effective to unlock the associated locking means when the related sliding member is moved in response to actuation of the operating means associated therewith.

13. A coin-control mechanism comprising a pair of plates spaced apart a distance slightly greater than the thickness of a coin of predetermined denomination, means to direct a coin along a predetermined path between said plates,

a plurality of sliding members arranged edge to edge between said plates, blocking members pivotally mounted on one face of one of said plates, each including a lug normally extending between the plates to prevent movement of the sliding members, a cam element carried by each sliding member slidably connected to a related locking member adapted to be rendered effective to unlock the related locking member when a coin is aligned with the related sliding member between the plates, and a support normally lying in the path of the coins to retain a coin in such alignment.

14. A coin-control mechanism comprising a pair of plates spaced apart a distance slightly greater than the thickness of a coin of a predetermined denomination, means to direct a coin along a predetermined path between said plates, a plurality of sliding members arranged edge to edge between said plates, said members having abutting shoulders on their opposed edges to render said members selectively movable in succession, blocking members pivotally mounted on one face of one of said plates, each including a lug normally extending between the plates to prevent movement of the sliding members, a cam element carried by each sliding member slidably connected to a related locking member adapted to cam the related locking member out of locking position when a coin is aligned with the related sliding member between the plates, a support to retain said coin in such alignment, and means operable independently of the coin-control mechanism to move the support out of the coin path so that said coin may be discharged without actuation of the coin-control mechanism.

HARRY B. STONER.
